(57) **CLAIM**

The ornamental design for a round bucket, as shown and described.

DESCRIPTION

FIG. 1 is a front perspective view of the round bucket show a first embodiment of my new design;

FIG. 2 is a top view without the lid thereof;

FIG. 3 is a top view with the lid thereof;

FIG. 4 is a rear view thereof;

FIG. 5 is a side view thereof;

FIG. 6 is the opposite side view thereof;

FIG. 7 is a front view thereof;

FIG. 8 is a front perspective view of a second embodiment thereof;

FIG. 9 is a top view without the lid thereof;

FIG. 10 is a top view with lid thereof;

FIG. 11 is a rear view thereof;

FIG. 12 is a side view thereof;

FIG. 13 is the opposite side view thereof;

FIG. 14 is a front view thereof;

FIG. 15 is a front perspective view of a third embodiment thereof;

FIG. 16 is a top view without the lid thereof;

FIG. 17 is a top view with the lid thereof;

FIG. 18 is a rear view thereof;

FIG. 19 is a side view thereof;

FIG. 20 is the opposite side view thereof;

FIG. 21 is a front view thereof;

FIG. 22 is a front perspective view of a fourth embodiment thereof;

FIG. 23 is a top view without the lid thereof;

FIG. 24 is a top view with the lid thereof;

FIG. 25 is a rear view thereof;

FIG. 26 is a side view thereof;

FIG. 27 is the opposite side view thereof; and,

FIG. 28 is a front view thereof.
